LEWIS C. HUFFORD, OF REDONDO BEACH, CALIFORNIA

APPLE GRINDER

Application filed July 19, 1927. Serial No. 206,841.

This invention relates to a comminutor or grinder for apples and like vegetables or fruit. In the production of cider from apples, it is current practice to reduce the apples to small particles by cutting or grating them, and to express the juice from the comminuted apples by suitable means such as a press. It has been common practice to perform the comminution by means of rotary cutters or rasps housed within a drum. It is desirable to have a compact cutter of great capacity, high speed and efficiency and the primary object of this invention is to provide a device attaining these objects. To 15 this end, a more specific object of this invention is the provision of a grinder having a vertical axis rotary cutter of drum type and including details of structure contributing to economy of operation and construction, 20 simplicity and ease of manipulation.

These objects together with other objects and corresponding accomplishments are obtained by means of the embodiment of my invention illustrated in the accompanying 25 drawings in which:

Fig. 1 is an elevation of a complete comminutor; Fig. 2 is a plan view thereof, the supporting frame being omitted; Fig. 3 is a vertical section, showing the cutting drum 30 in elevation; Fig. 4 is a section as seen on the line 4-4 of Fig. 3; Fig. 5 is an axial section through the cutter drum showing a fragment of the upper end; Fig. 6 is an elevation showing a fragment of a cutter drum 35 of different construction; Fig. 7 is a section as seen on the line 7-7 of Fig. 6 on an enlarged scale; and Fig. 8 is an axial section through the structure shown in Fig. 6 showing the lower end of the drum.

Referring with more particularity to Figs. 1 to 5 inclusive, a supporting frame for the mechanism is indicated by 10. Secured in a table or base 11 on the frame by any well known means and depending therefrom is 40 the grinder proper. A cylindrical neck 12 is provided with a flange 13 and pivotally secured to the neck are clamps 14 arranged to underhang the flange. The neck is provided with a throat 15 and a chamber at one side 45 thereof constituting a drive gear housing in

which is mounted bevel gearing 16 whereby a drive shaft 17 operates a vertical shaft 18. The shaft 18 has radial thrust bearings at the top and bottom and is arranged to carry a drum. Detachably secured to the neck 12 55 is a casing 19 of frusto-conical shape. At the larger end it is provided with a flange 20 corresponding to flange 13, so arranged that the clamps 14 may be engaged therewith to detachably hold the case to the neck. The 60 lower end thereof is formed with a bridge 21 having a hub 22 provided with a bearing for the lower end of shaft 18. There are ribs or corrugations 23 on the inner surface of the casing. Fixed to the shaft 18 is a drum 65 having an imperforate cylindrical shell 24. At the end of the shell are arms 25 meeting in a hub 26 which serves for securing the drum to the shaft 18. Formed in the shell are parallel slots arranged at an angle to the 70 shaft constituting flights of relatively great pitch. These slots receive tooth bars 27 which are bevelled to an edge as shown in Fig. 4 there being several teeth formed therein along the length of each bar. The bars are 75 secured in position by a clamping cap 28 at the top and a clamping ring 29 at the bottom, the cap being best shown in Fig. 5. Each of the tooth bars is provided at the ends with extensions 30, see Fig. 5, which are received 80 in corresponding recesses in the clamping cap and ring. The latter are secured to the ends of the shell by means of screws. The construction is such that when the shaft 18 is 85 rotated, the drum is rotated.

In Fig. 1 a receiving member 31 is shown disposed upon the table 11. This is preferably a revolving hopper adapted to hold apples which are fed to the mouth at the throat 15 and thence into the case 19. The 90 details of the hopper are not shown as they are not pertinent to the present invention. Shaft 18 may be driven from an electric motor 32 or any other convenient source of power.

The operation of the device is as follows: Apples are fed from the hopper to the case and lodge in the space between drum 24 and the wall of casing 19. Rotation of the drum tends to turn the apples, the corrugations 23 100

impeding such turning. The angular formation of the bars tends to aid gravitational force in moving the apples from the inlet end at the top downwardly to the small or outlet end of the space between the drum and the casing. During the operation, the teeth on the drum rasp and cut the apples, the latter being turned over to present new surfaces, reduced in size and at the same time being urged downwardly and finally passing through the space between the drum and casing at the lower or outlet end, this space determining the size of the particles in the pulp. It is obvious that the entire space around the drum may be filled with apples in various stages of comminution. The apple particles move downwardly and through the discharge passage at the lower end, the pulp being received in a suitable container, not shown. From there it may be delivered to the press. The machine is not for the purpose of extracting the juice, but for the purpose of dividing the apples into small particles.

Whereas, the tooth bars are a convenient means of rasping and dividing the apples to produce pulp, it will be obvious that other types of cutters may be used. Another form is shown in Figs. 6 to 8a. A cylindrical shell 33 has tongues 34 pressed outwardly from its body and arranged in spiral lines. The shaft 18 has spider 35 at the lower end and a ring 36 for securing the shell 33 to the spider. Various other mechanical variations may be resorted to without departing from the invention and will be apparent from the appended claims.

What I claim is:

1. In a device of the character described, a casing having an upright frusto-conical chamber, a rotatable cylindrical cutter drum disposed therein, there being lines of spaced cutting teeth on said drum arranged in parallel spiral rows of relatively great pitch, said casing having longitudinally extending corrugations on its inner surface.

2. In a device of the character described, a casing having an upright frusto-conical chamber, a rotatable cutter drum disposed therein providing an annular space isolated from the chamber of said drum, said drum having a shell with spiral grooves on its periphery of relatively great pitch, cutter bars provided with spaced teeth inset in said grooves, clamping means engaging said bars and for detachably holding the bars to said drum.

3. In a device of the character described, a casing, an upright rotatable cutter drum disposed therein so as to provide a space between of decreasing cross sectional area from an inlet end to an outlet end for gravitational travel of material therethrough, there being lines of spaced cutting teeth on said drum arranged in flights of relatively great pitch, said casing having corrugations longitudinally extending from end to end to impede revolution

about said drum of the material being cut and to guide the same from inlet to outlet.

In witness that I claim the foregoing I have hereunto subscribed my name this 21st day of June, 1927.

LEWIS C. HUFFORD.
